United States Patent Office

Des. 177,712
Patented May 22, 1956

177,712

HAT

Billie Royse Boydston, Los Angeles, Calif.

Application December 20, 1954, Serial No. 33,612

Term of patent 3½ years

(Cl. D3—13)

Fig. 1

Fig. 2

Fig. 3

Fig. 1 is a side perspective view of a hat embodying my new design;

Fig. 2 is a front perspective view of the same; and

Fig. 3 is a rear elevational view of the same.

I claim:

The ornamental design for a hat, substantially as shown.
